ATTORNEY

UNITED STATES PATENT OFFICE.

ALBERT STERN, OF NEW YORK, N. Y.

CLIP HOLDER FOR BABY CARRIAGES.

Application filed July 17, 1922. Serial No. 575,725.

To all whom it may concern:

Be it known that I, ALBERT STERN, a citizen of Hungary, having declared my intention of becoming a citizen of the United States, and a resident of the borough of Manhattan, in the county and State of New York, have invented a new and useful Clip Holder for Baby Carriages, of which the following is a specification.

10 My invention is a cover clip and holder for baby carriages and the object is to provide a highly efficient device of this character, possessing special utilities as will appear.

15 In the accompanying drawings forming a part hereof:

Fig. 1 is a perspective view of a baby carriage, with a blanket or cover over the interior of its body, the end of the cover being disposed over the rolled end edge of the body where it is caught by a couple of the clips;

20 Fig. 2 is a vertical section through the wall of the body and a portion of the cover, showing the clip in edge elevation; and

25 Fig. 3 is an elevation of the clip looking at right angles to Fig. 2.

The clip A is formed from a band of spring metal or other suitable material which is bent into a substantially round, or somewhat laterally flattened or compressed, loop 1, the form and proportions of which adapt it to embrace the rolled edge a of the end wall b of the body c of a 30 baby carriage, together with the end portion of the cover d, as seen in Fig. 2.

The inner terminal of the loop is curled to form a foot 2 immediately adjacent the restricted mouth of the loop. This foot 35 overlies the cover where it passes inward

and forward from the clip over the interior of the body, restraining the same from rising above a level sufficiently below the top of the body for protection, while allowing proper room for the infant and its pillow, or 45 other bedding, and covers.

The outer terminal of the loop is prolonged substantially straight downward, forming a limb 3, which presses against the outer side of the wall of the body and the 50 interposed end of the cover. This extended frictional clasp beneath the overhang of the roll a insures that the cover will not become loosened either by the wind or kicking of the infant. Its extremity bent outward and upward into an open hook 4 affords a finger catch for drawing the clip 55 down, besides providing a support whereon to hang a handbag or other parcel B in order to relieve the person pushing the carriage. A pair of the clips will usually be used as shown, and their hook portions located below and immediately in front of the handle e of the carriage are of manifest 60 convenience.

65 What is claimed as new is:

A baby-carriage clip holder comprising a substantially circularly looped resilient band adapted to embrace the edge of a baby-carriage body and the end of a cover 70 or robe, the inner terminal of the loop being a short out-turned foot to stand above the inward stretch of the robe, and the outer extremity having a downwardly prolonged flat limb overhung by the outer side 75 of the loop to press against the outer side of the body wall, and an outwardly and upwardly bent hook at the extremity of said limb.

ALBERT STERN.
